UNITED STATES PATENT OFFICE.

FRANK D. BELKNAP, OF NEW YORK, N. Y.

STENCIL-CARD.

SPECIFICATION forming part of Letters Patent No. 573,850, dated December 29, 1896.

Application filed February 28, 1896. Serial No. 581,106. (No model.)

To all whom it may concern:

Be it known that I, FRANK D. BELKNAP, a citizen of the United States, residing at New York, in the county of New York and State 5 of New York, have invented certain new and useful Improvements in Stencil-Cards; and I do hereby declare the following to be a full, clear, and exact description of the invention, such as will enable others skilled in the art 10 to which it appertains to make and use the same.

My invention relates to stencil-cards for use in addressing-machines; and it consists of an improved form of such card, together with an 15 improved method of connecting a series of cards together for use in the addressing-machine.

The general nature of my invention and its preferred form are both disclosed in accompanying sheet of drawings, in which—

Figure 1 is a view of a series of stencil-cards connected together according to my invention. Fig. 2 is an improved form of connecting said cards together, in which they are 25 spaced differently from the manner disclosed in Fig. 1. Fig. 3 is a detailed plan view of the improved form of stencil-card. Fig. 4 is a cross-section on line 4 4, Fig. 3. Fig. 5 is an end view showing the cards of Fig. 1 folded 30 up, and Fig. 6 is an end view showing the cards of Fig. 2 similarly folded.

Throughout the drawings like reference-figures refer to like parts.

1 1^a 1^b 1^c 1^d, &c., constitute a series of stencil-cards which are connected together in any manner permitting them to be folded one upon the other, but preferably by pasting strips 2 2 along the ends of the cards. Sufficient space is left between the adjacent edges 3 3 of the 40 cards to permit of their being folded up, as shown in Fig. 5.

Fig. 2 shows a series of cards with every other card, as 1^a 1^c, removed and leaving the remaining cards 1 1^b 1^d spaced at a distance 45 approximately equal to the width of the cards. This permits the cutting out or insertion of any card or number of cards without changing the manner of folding of the rest of the string, as would be necessary in the arrangement 50 shown in Fig. 1.

4, Fig. 3, indicates the stencil-sheet on

which the address is written, and this is pasted to the reinforcing-frame of rectangular section 5. The pasting is preferable at the intermediate points 7 7 along the sides of such frame only. On the opposite side of the stencil-sheets, overlapping its ends, are placed the reinforcing-strips 6 6, pasted to the frame 5 along the ends 5^a 5^b thereof, so as to hold the ends of the stencil-sheet between the opposing strips 6 and 5^a, 6 and 5^b. The stencil-sheet, however, does not adhere to the strip 6 at all and does not adhere to the frame 5 except at the points 7 7, the paste at the ends being all outside of the dotted lines 8 8. 65

The operation of my invention is as follows: The string of cards is fed through the addressing-machine by any simple feed apparatus which may catch the edges 3 of the cards, and when not in use the cards may be folded 70 up, as shown in Figs. 5 and 6. The arrangement shown in Figs. 1 and 5 has the advantage that the clean surfaces of the cards are always together and the inked faces together. The arrangement shown in Fig. 2 has not this 75 point of advantage, but it has the additional one that any number of cards can be removed or inserted without bothering to rearrange the remaining portions of the folded string, as would be the case if one of the cards were removed from the pile shown in Fig. 5.

The form of card illustrated in Figs. 3 and 4 is particularly advantageous for this method of attachment, because its greatest strength is along the ends to which the strips 2 are 85 pasted, and it is in this direction that the strain of the feeding action comes. The card is equally adapted for use in separate form wherever the feeding mechanism operates in the line of the strips 6 6, and is applied to the 90 card at or near the extreme ends.

The advantages of the invention are, first, the improved form of card, which gives strength with lightness and is devoid of any tendency to curl; second, the attachment of 95 cards one to another, so that they may be folded together, by reason of the fact that the connection between any two cards is capable of flexure through three hundred and sixty degrees, which permits all of the good features of the card system to be realized without the possibility of loss of single cards and 100

simplifies the necessary feed mechanism of the addressing-machine to a very great degree.

I find that in certain cases when the stencil-sheets 4 are sufficiently thick and stiff the additional reinforcing-strips 6 may be dispensed with and the stencil-sheet held to the reinforcing-frame 5 by some adhesive material at the intermediate points 7 7, as before.

10 Having therefore described my invention, what I claim as new, and desire to protect by Letters Patent, is—

1. The improved stencil-card which consists of the combination of the stencil-sheet 15 and rectangular reinforcing-frame which is attached to one side of said sheet by pasting to the two longer sides thereof at intermediate points, and the detached reinforcing-strips which are pasted to the ends of the reinforce-

ing-frame and overlap the stencil-sheets along 20 its ends but do not adhere thereto, substantially as described.

2. The combination of the series of stencil-cards and the flexible connections between their adjacent edges, said connections being 25 capable of flexure through three hundred and sixty degrees whereby they may be folded one upon the other, the space between each two adjacent cards being approximately equal to the width of the cards, substantially as described.

In testimony whereof I affix my signature in presence of two witnesses.

FRANK D. BELKNAP.
